UNITED STATES PATENT OFFICE.

GEORG OPPERMANN, OF HANOVER, GERMANY, ASSIGNOR TO THE WESTINGHOUSE AIR BRAKE COMPANY, OF PITTSBURG, PENNSYLVANIA, A CORPORATION OF PENNSYLVANIA.

FLUID-PRESSURE BRAKE.

SPECIFICATION forming part of Letters Patent No. 772,903, dated October 18, 1904.

Application filed December 6, 1902. Serial No. 134,100. (No model.)

To all whom it may concern:

Be it known that I, GEORG OPPERMANN, a subject of the Emperor of Germany, residing in the city of Hanover, Germany, have invented 5 a certain new and useful Improvement in Fluid-Pressure Brakes, of which improvement the following is a specification.

My invention relates to fluid - pressure brakes, and has for its object to provide an 10 improved brake apparatus by means of which a more perfect and complete control may be had of the pressure with which brakes are applied.

With the present form of automatic air-brake as ordinarily used the brake-cylinder pressure cannot be accurately graduated during the release, thus rendering it more difficult to stop a train exactly upon a given spot without loss of time and making it almost 20 impossible to control the train in descending heavy grades so as to keep a uniform speed.

The object of my present invention is to overcome these difficulties, at the same time retaining all the advantages of the present automatic air-brake as well as other advantages 25 hereinafter set forth which are calculated to afford increased reliability of action under any condition of working and greater security against failure of operation. This object

30 may be attained by the combination of any automatic brake apparatus with an equilibrium brake device having a piston normally subjected to equal pressures on its opposite sides and being applied by reducing the pressure upon one side, the same operating in 35 conjunction with a pressure-reducing valve so as to charge the automatic brake apparatus with a higher degree of pressure than the equilibrium-brake, both brake devices being 40 connected to the same main train-pipe.

In the accompanying drawing the figure shows one such form of combined fluid-pressure brake apparatus embodying my invention.

45 The main train-pipe 1 is provided with the usual branch pipe 2, connected to the triple

valve 3, auxiliary reservoir 4, and brake-cylinder 5, all of which comprise the ordinary automatic air-brake apparatus as applied to a car. In accordance with my improvement 50 I provide an additional equilibrium brake device 6, the chamber 7 on one side of the piston 8 forming the reservoir, which may be of any desired shape or capacity, and the chamber 9 constituting the brake-cylinder, which 55 is connected to the train-pipe 1 by means of branch pipe 10, containing the pressure-reducing valve 11.

Any suitable form of connections between the respective brake-pistons and brake-rigging whereby the brake-cylinders of the two devices coöperate in the application of the brake may be made, one such arrangement being indicated in the drawing, showing the slotted ends of the piston-rods connected to 65 opposite ends of the lever 12 of the brake-rigging.

The small puppet-valve 13 of the pressure-reducing valve 11 is actuated by the diaphragm 14 in the usual way, but is disconnected therefrom, so as to be closed by pressure from train-pipe 1 when the pressure in cylinder 9, acting on diaphragm 14, is sufficient to depress the same against the adjustable spring 15 and adapted to open freely for 70 the passage of air from the cylinder 9 to the train-pipe 1 whenever the pressure in the train-pipe falls below that to which the pressure-reducing valve 11 is adjusted.

The operation is as follows: Compressed air 80 admitted from the main reservoir flows through the train-pipe 1 and through branch pipes 2 and 10 into the combined brake apparatus, charging the triple valve 3 and auxiliary reservoir 4, as well as both chambers 7 85 and 9 of the equilibrium brake device, with air under pressure. The cup-leather packing of the piston 8 permits the free passage of air from cylinder 9 to reservoir-chamber 7, but prevents it from flowing past the piston in the 90 opposite direction. When the pressure in the cylinder 9 and chamber 7 has reached the

point at which the pressure-reducing valve 11 is set, this valve closes, thus shutting off further supply of air to the equilibrium-brake 6. The feed to the triple valve and auxiliary reservoir is not interrupted; however, and these parts will be charged up to full working train-pipe pressure. Upon a slight reduction of pressure being made in train-pipe 1 the triple valve operates in the usual way 10 to admit air under pressure from the auxiliary reservoir 4 to the brake-cylinder 5, thus forcing the rod of piston 16 against the brake-lever 12 and applying the brakes with moderate force. Each further reduction of train-pipe 15 pressure will cause the triple valve to again discharge air from reservoir 4 to brake-cylinder 5, and so increase the force with which the brakes are applied. The equilibrium-brake remains inactive until the train-pipe pressure 20 has been reduced below the point to which the cylinder 9 is charged, as determined by the adjustment of the reducing-valve 11. Compressed air then flows from cylinder 9 back through the reducing-valve and branch pipe 10 25 to the train-pipe 1, and any further reduction in said train-pipe pressure is thereafter also produced in the cylinder 9. Since air cannot flow out from reservoir-chamber 7, an excess of pressure is maintained therein which now 30 forces piston 8 into cylinder 9, thus exerting additional power upon the brake-lever 12 corresponding to the difference of the pressures in chambers 7 and 9. When it is desired to release the brakes, the train-pipe pressure is increased and at first not being great enough 35 to move the triple valve against the equalized auxiliary-reservoir pressure flows into the equilibrium-cylinder 9. The pressure in this cylinder then increases in the same proportion 40 as the pressure is raised in the train-pipe, and the braking force exerted by piston 8 may therefore be reduced or increased at will by merely raising or lowering the train-pipe pressure. As soon as the train-pipe pressure 45 is raised above the equalized pressure in the auxiliary reservoir 4 the triple valve is moved to release position and the pressure from brake-cylinder 5 is discharged to the atmosphere. The pressure-reducing valve 11 may 50 be adjusted so as to charge the equilibrium-brake 6 with any desired pressure within certain limits, and this adjustment will determine the relative operation of the two brake-cylinders 5 and 9. If the valve 11 is adjusted to 55 close at a train-pipe pressure sufficiently below normal, the automatic brake will be fully applied before the equilibrium-brake begins to act, and then upon increasing said train-pipe pressure the latter brake will be fully released before the release of the automatic 60 brake. The reducing-valve may also be adjusted to start the action of the equilibrium-brake just when the full power is obtained in cylinder 5 and to effect the release of said

cylinder at about the same moment as the equilibrium-brake has been fully released. In any case a sufficient margin should be left between the commencement of the action of the two brakes to insure the quick action of the triple valve being promptly obtained before air can flow from equilibrium-cylinder 9 into the train-pipe. 70

It will now be evident from the foregoing description that I have provided an improved combined brake apparatus including two 75 brake devices, each being complete in itself, whereby if one should fail or become inoperative the other device may still be used, both brake devices being operated and controlled by a single line of train-pipe and 80 adapted to apply the brakes with great force, which force may be gradually reduced or again increased as circumstances may require, thus securing perfect control for trains in descending heavy grades and also making stops 85 at certain points easy.

Various changes and modifications in the general arrangement of parts may be made within the scope of my invention.

Having now described my invention, what 90 I claim as new, and desire to secure by Letters Patent, is—

1. An automatic fluid-pressure brake device comprising a train-pipe, triple valve, auxiliary reservoir and brake-cylinder, in combination 95 with an equilibrium brake-cylinder connected to the train-pipe and operated by variations of pressure therein.

2. In an automatic fluid-pressure brake apparatus, the combination with a train-pipe, triple valve, auxiliary reservoir and brake-cylinder, of an equilibrium brake-cylinder connected to the train-pipe and a pressure-reducing valve in said connection. 100

3. In a fluid-pressure brake apparatus, the combination with a train-pipe, auxiliary reservoir, triple valve and brake-cylinder, of an additional brake-cylinder having a piston normally exposed to equal pressures on its opposite sides, and a connection for establishing 110 communication between the train-pipe and the additional brake-cylinder. 110

4. In a fluid-pressure brake apparatus the combination with a train-pipe, auxiliary reservoir, triple valve and brake-cylinder, of an additional brake-cylinder having a piston normally exposed to equal pressures on its opposite sides, a passage leading from one side of said piston to the train-pipe and a pressure-reducing valve located in said passage. 115

5. In a fluid-pressure brake apparatus, the combination of an automatic brake device and an equilibrium brake device both connected to the same train-pipe. 120

6. In a fluid-pressure brake apparatus, the combination with a train-pipe, triple valve, auxiliary reservoir and brake-cylinder, of an additional equilibrium brake-cylinder and

reservoir, a pipe or passage leading from the train-pipe to the latter brake-cylinder and means for feeding fluid under pressure from train-pipe to the reservoir of the equilibrium brake.

7. The combination of an automatic air-brake device connected to a train-pipe, an equilibrium brake device also connected to

the same train-pipe and a pressure-reducing valve located in said latter connection. 10

In testimony whereof I have hereunto set my hand.

GEORG OPPERMANN.
